WIRE SPRING

William H. Neely, Cleveland, Ohio, assignor to
 The Universal Wire Spring Company, Cleve-
 land, Ohio, a corporation of Ohio

Application September 26, 1949, Serial No. 117,840

5 Claims. (Cl. 155—179)

1

This invention relates to flat springs of sinuous or similar shape such as used for seats, backs of seats, flat cushions, etc. Springs of this type when attached to or mounted on frame structures develop in their seating or resting portions, particularly when loaded, excessive stiff areas and excessive yielding areas, caused by either excessive or insufficient bending stresses, the excessive stiff areas being generally present in springs rigidly secured to a frame structure, and excessive yielding areas being generally present in springs pivotally secured to a frame structure, though both excessive stiff or excessive yielding areas may be present in springs rigidly or pivotally secured to a frame structure. This undesired reaction of this type of flat spring has partly been overcome by offsetting some of the convolutions of the springs with respect to the general plane of their seating or resting portions, a rather costly and often insufficient procedure in manufacturing these flat springs.

The primary object of the present invention is the provision of a flat, substantially sinuously corrugated or zigzag shaped wire spring in which in certain areas of the spring the cross wires connecting substantially parallelly arranged loops are spaced differently from the cross wires in other areas of such spring to increase and reduce in these certain areas the stiffness and yielding action of the spring and provide for proper seating and resting comfort in seat and back structures embodying these springs.

Stiffness and yielding action of predetermined areas of flat, sinuously or zigzag shaped wire springs, furthermore, depend on the diameter of the loops in these areas, which loops generally control the angular relation of the loop-connecting cross wires with respect to the axis of the spring.

Another object of the present invention, therefore, is the provision of a flat, substantially sinuously corrugated or zigzag shaped wire spring in which in certain areas of the spring the cross wires connecting the substantially parallelly arranged loops are spaced differently from the cross wires of other areas of such spring, and in which in said certain areas the loops have diameters different from the loops of the other areas to control the angular relation of the loop-connecting cross wires with respect to the axes of the springs, and properly increase and reduce in these certain areas stiffness and yielding action of the spring for proper seating and resting comfort in seat and back structures embodying these springs.

2

In addition, the invention has other marked improvements and superiorities which radically distinguish it from presently known structures. The improvements or superior characteristics embodying certain novel features of construction are clearly set forth in the appended claims, and several preferred embodiments of the invention are hereinafter shown with reference to the accompanying drawings forming part of the specification.

In the drawings:

Fig. 1 is a plan view of a fragmentary portion of the seating or resting portion of a wire spring formed from zigzag shaped wire having equally sized loops throughout and a portion in which the distance between adjacent loop-connecting cross wires is shorter than the distance between adjacent cross wires in other portions of the resting portion of said zigzag shaped wire;

Fig. 2 is a plan view similar to Fig. 1 with the exception that the diameter of the wire loops in the portion referred to above is smaller than the diameter of the loops in the other portions of the zigzag shaped wire spring;

Fig. 3 is a plan view of a fragmentary portion of the seating or resting portion of a zigzag shaped wire spring, including a portion in which the distance between adjacent loop-connecting cross wires is longer than the distance between the cross wires in other portions of the resting portion of said zigzag shaped wire spring;

Fig. 4 is a plan view of a fragmentary portion of the seating or resting portion of a zigzag shaped wire spring including definite portions in which the distance between adjacent, loop-connecting cross wires is either shorter or longer than the distance between adjacent cross wires in other portions of the resting portion of said zigzag shaped wire spring;

Fig. 5 is a perspective view of a wire spring member embodying a resting surface including a portion having relatively decreased stiffness with respect to other portions of the wire spring member; and

Fig. 6 is a perspective view of a wire spring member embodying a resting surface including portions having relatively increased and decreased stiffness with respect to other portions of the wire spring member.

Referring now more particularly to Figs. 1 through 4 of the drawings representing fragmentary sections of the seating or resting portions of sinuously corrugated or zigzag shaped wire springs commonly used in back rest and seat constructions for upholstered furniture and automo-

bile seat structures, reference numeral 2 denotes a steel wire bent to sinuous or zigzag shape so that the resting portion 3 of the wire structure includes loops 4 extended substantially parallel to each other and connected with each other by cross wires 5. The thus constructed resting portion 3 (see Fig. 1) which embodies equally-sized loops throughout, includes a portion 6 in which the distance between adjacent cross wires 5' is shorter than the distance between adjacent cross wires 5 in portions 7 and 8 of resting portion 3 positioned adjacent to portion 6. As the spacing of cross wires 5' in portion 6—shorter than the spacing of cross wires 5 in portions 7 and 8—decreases the relative stiffness of portion 6 with respect to the stiffness of portions 7 and 8, proper location of portions similar to portion 6 in the resting portion of a spring structure affords a highly practical means to provide for proper seating and resting comfort in seat and back rest spring structures.

The seating and resting comfort of the above described resting portion of a spring structure can additionally be improved by decreasing the diameter of the loops of the portion 6 so that the cross wires 5' extend substantially at a right angle to the axis of the resting portion. Such a structure is disclosed in Fig. 2 in which the resting portion 9 embodies a portion 10 having a distance between adjacent cross wires 11 shorter than the distance between adjacent cross wires 11' in portions 12 and 14, positioned adjacent to portion 10, and having loops 15 which are smaller in diameter than loops 16 in the portions 12 and 14, all for the purpose of arranging the cross wires 11 in portion 10 at a substantially right angle to the axis of resting portion 9 and increasing the relative length of cross wires 11 with respect to cross wires 11' to decrease the torsional resistance of cross wires 11 with respect to the torsional resistance of cross wires 11'.

Different spacing of the cross wires of sinuously corrugated or zigzag shaped wires can also (see Fig. 3) be utilized to locally increase the stiffness of the seating portion of a wire structure. In this case the resting portion 13 of the wire structure includes a portion 17 in which the distance between adjacent cross wires 18 is longer than the distance between adjacent cross wires 18' in portions 19 and 20, positioned adjacent to portion 17.

For utmost seating and resting comfort of the resting portion of a zigzag shaped wire spring structure, different spacing of the cross wires of the spring structure can be used for locally increasing and decreasing the stiffness of the resting surface as shown in Fig. 4. In this case the resting portion 21 of the wire structure includes portions 22 and 23 having a distance between adjacent cross wires 24 in portion 22 shorter than the distance between the normally spaced cross wires 24' of the spring structure, and in which the distance of the adjacent cross wires 24'' in portion 23 is longer than the distance between adjacent cross wires 24 in portion 22 and the distance between the normally spaced cross wires 24' of the spring structure.

In addition to a control of seating and resting comfort on the resting portions of zigzag-shaped wire spring structures, different spacing of the cross wires of the wire spring structure can be used in the supporting portions of these spring structures, which generally support the spring structure in elevated position on open frame structures or similar devices. This is disclosed in the wire springs shown in Figs. 5 and 6. In these

figures spring structure 25 (see Fig. 5) embodies a zigzag-shaped supporting or resting portion 26 including a portion 27 with more closely spaced loop-connecting cross wires 28 than the normally spaced loop-connecting cross wires 28' of the resting portion 26, and a portion 29 with more widely spaced loop-connecting cross wires 28'' than said cross wires 28'. The thus constructed resting portion has integrally extended from its front end 10 a rearwardly and downwardly extended supporting arm 30 which has integrally extended therefrom a forwardly extended arm 31 adapted to be used for securing said latter arm to the front rail of a frame (not shown) and has integrally extended from its rear end a forwardly inclined supporting arm 32 adapted to be used for securing said resting portion to the rear rail of a frame (not shown). As shown, the rearwardly and downwardly inclined extended supporting arm 30 15 of spring structure 25 includes a portion 33 having its loop-connecting cross wires 34 spaced more closely with respect to each other than the other loop-connecting cross wires 34' of said arm to decrease its stiffness and increase its yielding action, and the forwardly inclined supporting arm 32 includes a portion 35 having its loop-connecting cross wires 36 spaced wider with respect to each other than the other loop-connecting cross wires 36' of said arm to increase its stiffness and decrease its yielding action, all for the purpose of proper control of the spring structure for proper comfort and yielding action under load.

Spring structure 37 (see Fig. 6) is substantially identical in general outline with spring structure 25 with the exception that zigzag-shaped supporting or resting portion 38 has integrally extended from its rear end an upwardly and rearwardly extended arm 39. This spring structure includes in the seating or resting portion 38 portions 40 and 41 having their loop-connecting cross wires 42 and 42' spaced differently to increase and decrease stiffness and decrease and increase the yielding action in portions 40 and 41. In addition spring structure 37 includes in its upwardly and rearwardly extended arm 39 a portion 43 having its loop-connecting cross wires 44 spaced more widely with respect to each other than the other loop-connecting cross wires, to increase its stiffness and decrease its yielding action.

The shown and described location of areas of decreased and increased stiffness and yield in sinuously corrugated springs is not necessarily restricted to the structures disclosed and described, same being merely given by way of example of the invention.

Having thus described my invention, what I claim is:

1. An integral, elongated wire spring for seat structures including a flat, sinuously corrugated, resting portion and supporting means for said resting portion extended from opposite ends thereof, said supporting portion embodying successive left and right handed loops connected by cross wire members spaced from each other a predetermined distance and other successive left and right handed loops connected by cross wire members spaced from each other a predetermined distance different from said first distance to provide a resting portion including areas of different yield to loads placed thereon.
2. An integral, elongated wire spring for seat structures including a flat, sinuously corrugated, resting portion and supporting means for said resting portion integrally extended from oppo-

site ends thereof, said resting portion embodying successive left and right handed loops connected by cross wire members spaced from each other a predetermined distance and other successive left and right handed loops connected by cross wire members spaced from each other a predetermined distance shorter than said first distance to provide the resting portion with a localized area more readily yielding to loads placed thereon than other areas of such resting portion.

3. An integral, elongated wire spring for seat structures as described in claim 2, wherein the more readily yielding area of the resting portion is arranged near its rear end portion.

4. In an integral, elongated wire spring for seat structures, a flat, sinuously corrugated resting portion and supporting arms for said resting portion extended from opposite ends thereof, said resting portion embodying successive left and right handed loops connected by cross wire members, said corrugated resting portion including areas, each of which has its connecting cross wire members spaced equally from each other and differently from the connecting cross wire members of other areas.

5. In an integral, elongated wire spring for seat

10

structures, a flat, sinuously corrugated, resting portion and sinuously corrugated, supporting arms for opposite ends of said resting portion integrally extended therefrom, said resting portion and supporting arms including areas each of which has its connecting cross wire members spaced from each other an equal distance different and shorter than the spacing of the connecting cross wire members of other areas.

6 WILLIAM H. NEELY.
